CLAIM

The ornamental design for a parking unit for a portable
telephone or similar article, as shown and described.

DESCRIPTION

FIG. 1 is a left side, top and front end perspective view
of a parking unit for a portable telephone or similar
article showing my new design;

FIG. 2 is a left side elevational view thereof, the side
opposite being a mirror image;

FIG. 3 is a top plan view thereof; and

FIGS. 4 and 5 are respectively rear and front end eleva-
tional views thereof.

FIG. 1

FIG. 2

FIG. 3

FIG. 4

FIG. 5
